UNITED STATES PATENT OFFICE.

CHARLES C. PRINZ, OF LEXINGTON, KENTUCKY.

TRAFFIC-INDICATOR.

1,148,986.

Specification of Letters Patent.

Patented Aug. 3, 1915.

Application filed March 24, 1914. Serial No. 826,986.

To all whom it may concern:

Be it known that I, CHARLES C. PRINZ, a citizen of the United States, residing at Lexington, in the county of Fayette and State of Kentucky, have invented new and useful Improvements in Traffic-Indicators, of which the following is a specification.

This invention relates to traffic indicators, the object in view being to provide a simple indicating device by means of which the operator of an automobile or other motor vehicle may notify a traffic policeman as to the direction which he intends to follow, for example, at a congested street crossing.

15 By means of the device of this invention, the operator is enabled to indicate the direction he intends to take as above noted by the simple pressure of a switch which will cause the indicating pointer to move to the right 20 or to the left according to the direction in which he intends to turn the machine.

With the above and other objects in view, the invention consists in the novel construction, combination and arrangement of parts, 25 as will hereinafter be more fully described, illustrated and claimed.

In the accompanying drawings—Figure 1 is a front elevation of the traffic indicator of this invention, the same being broken 30 away to illustrate the contained mechanism. Fig. 2 is a vertical diametrical section through the same.

The traffic indicator contemplated in this invention comprises a case 1 which, in the 35 preferred embodiment of the invention, is cylindrical in shape and provided with a back wall 2 and a front panel 3 of clear glass while between the back and front of the case is arranged a panel 4 of ground or 40 frosted glass which will serve to diffuse the rays of light from an electric or other lamp 5 which is contained within the case 1 and located behind the panel 4.

Between the panels 3 and 4 is arranged an 45 indicating pointer 6 shown in the form of an arrow the same being mounted on a shaft 7 located centrally of the case 1 and journaled in the back of the case and also in an L-shaped bracket 8. Fast on the shaft 7 50 of the pointer 6 is a spur gear pinion 9 which meshes with and is actuated by a toothed sector 10 pivotally mounted at 11 on the bracket 8. The sector 10 carries a double ended armature 12 at opposite ends 55 of which are arranged electromagnets 13.

From one of the magnets 13 circuit wires

14 lead through posts 15 and 16 to a push button switch 17. From the other electromagnet, wires 18 lead through the post 15 and another post 19 to an additional push button switch 20. The switches 17 and 20 may be arranged on the dash of an automobile or other convenient supporting part of the machine, it being understood that the circuits of the two electromagnets include 60 a suitable source of electrical energy such as a magneto, battery or generator so that by pressing either one of the buttons 17 or 20 the appropriate electromagnet will be energized and therefore attract the armature 12 and consequently the sector 10 in a corresponding direction.

As indicated by full lines in Fig. 1, the pointer 6 normally hangs pendant or vertically and when either one of the magnets is 70 energized, the said pointer is caused to swing to a substantially horizontal position pointing either to the right or to the left as the case may be as indicated by dotted lines in 75 said figure.

80 While I have illustrated two push button switches 17 and 20 it will of course be understood that a single switch may be employed in the form of the ordinary lever switch movable to one side or the other of 85 the given point for the purpose of throwing into the circuit either one of the electromagnets.

85 By day light the pointer 6 will be visible through the clear glass panel 3 at the front 90 of the case while after dark the pointer 6 which is preferably of some opaque material will be clearly discernible in front of the panel 4 which as above stated is of ground or frosted glass or some equivalent material.

95 What I claim is:—

A traffic indicator for automobiles comprising a casing, a back plate therefor, a transparent panel forming a closure for the 100 front of said casing, a ground glass panel located between said front panel and back plate, a shaft journaled in said ground glass panel and back plate, a pointer fast on said shaft, and actuating means for said shaft 105 located between said back plate and ground glass panel and embodying a pinion having a fixed relation to said pointer and adapted to turn on the same axis therewith, a pendant oscillatory gravity centered toothed sector meshing with said pinion, an arcuate armature carried directly by said sector and 110

concentric to the axis thereof, oppositely located electromagnets arranged at the opposite extremities of said armature, an electric lamp located between said back plate and ground glass panel, and manually controlled means for independently energizing said magnets.

In testimony whereof I affix my signature in presence of two witnesses.

CHARLES C. PRINZ.
